FURNACE TILTING DEVICE

William E. Moore, Pittsburgh, Pa., assignor to
Delaware Engineering Corporation, a corpora-
tion of Delaware

Application October 11, 1941, Serial No. 414,661

7 Claims. (Cl. 121—46)

1

This invention relates in general to the furnace art and is particularly applicable to electric furnaces of the tilting type and will be described with reference thereto.

From time to time in the operation of a furnace it is necessary to tilt the furnace to discharge all or part of its contents. The apparatus of my invention enables the tilting to be readily performed. The apparatus consists of a cylinder and cooperating piston connected between a point on the furnace and a fixed support. One of the connections is a universal joint. The furnace is caused to tilt around a trunnion support by relative movement of the piston and cylinder.

In order to adjust the distance of movement of the furnace and thus its degree of tilt, I provide simple means permitting such adjustment, said means being enclosed in the cylinder and piston unit and readily accessible for adjustment, even when the unit is connected in operating position.

The mechanism is such as to provide for maximum travel of the cylinder and piston relative to one another, and is fluid operated to lift the furnace. The furnace is lowered by its own weight, and the distance of travel and the rate of lowering are controlled by regulating the discharge of the activating fluid, usually hydrocarbon oil having the desired physical characteristics.

The provision of a universal connection between the furnace and its tilting mechanism enables the apparatus to function smoothly and efficiently, even though portions of the furnace become warped permanently or temporarily due to the expansion and contraction caused by the heat of operation of the furnace.

In the drawings showing the present preferred embodiment of my invention, and in which like numerals are used to designate like parts throughout,

Figure 1 is a side view in elevation of a furnace, employing my tilting apparatus;

Figure 2 is a top plan view of the furnace shown in Figure 1;

Figure 3 is a view in elevation of the furnace, partly in section;

Figure 4 is a sectional view along the line IV—IV of Figure 1, but to an enlarged scale;

Figure 5 is a view, partly in section and partly in broken elevation of the piston and cylinder arrangement;

Fig. 6 is a view of the closed end of the cylinder;

Figure 7 is a sectional view along the line VII—VII of Figure 5;

Figure 8 is a sectional view along the line VIII—VIII of Figure 5;

2

Figure 9 is a sectional view along the line IX—IX of Figure 5; and

Figure 10 is a view of the closed end of the piston.

The drawings show an electric furnace, generally designated by the numeral 10, which is constructed in accordance with conventional practice. The furnace includes a metal shell 11 to the front of which two metal brackets 12 are rigidly secured on opposite sides of the pouring spout 13. The outer end of each bracket is journaled by the pins 14 between the bifurcated upper end of spaced-apart metal supports 15 which rest on a suitable foundation 16.

15 A pair of jacks 17 consisting of hydraulic cylinder C and piston P are connected between yoke-like brackets 18, secured to the shell 11, and bearing blocks 19 which are fastened to the bottom of a pit 20 formed in the foundation 16.

20 The brackets 18 are secured to the shell 11 at opposite sides thereof at a point above the convex bottom and to the left or rear of the vertical center line of the furnace as seen in Figure 1. The bearing blocks 19 are also placed to the left 25 of the vertical center line but closer to it than are the brackets.

The cylinder C is journaled in the brackets 18 by pins 21 and 22 which are received in the bracket and extend from a trunnion collar 23

30 which encircles the cylinder at a point above the center of the cylinder. A line through the longitudinal axis of the four pins 21 and 22 is parallel to the line through the centers of pins 14. The collar 23 is in turn journaled by pins 24 and

35 25 to the two longitudinally extending trunnion-bearing brackets 26 and 27 respectively which are welded to the outside of the cylinder at points on opposite sides of the collar. The pins 24 and 25 are in the same plane as the pins 21

40 and 22 of each cylinder and the axis passing through the pins 24 and 25 is at right angles to the axis passing through the pins 21 and 22. This arrangement is in effect a universal joint connection.

45 The piston P is hollow and is slidably received in and extends downwardly from the cylinder C. The lower end of the piston is closed by a piston end trunnion 28 in which there is a fluid admitting passage 29 leading from the outside

50 to the interior of the piston. The operation of the cylinder and piston is regulated by controlling the flow of actuating fluid under pressure, usually oil through the passage 29 by means of a valve 30 in known fashion. A hole 31 is provided 55 through the end of the trunnion, the axis of the

hole being parallel to the line passing through the center of pins 21 and 22. The end of the trunnion is rotatably connected to bearing block 19 by a bearing pin 33 which passes through the block 19 and through the hole 31 in the trunnion end; the pin 33 is parallel to the axis of the pins 21 and 22.

The cylinder C comprises a circular hollow member 34, one end of which is closed by a circular cylinder head 35 welded to the cylinder end. The cylinder head 35 has a circumferential flat portion 36 and a centrally located inwardly depressed portion or socket 37 having a central opening 38 extending through the end thereof. A bleed hole 39 is provided in the cylinder head near the flat portion 36 and extends upwardly into the depressed portion. A circular gland cap 40 having a central vent 41 closed by a screw 42 extends across the socket 37 and is attached to the flat portion 36 by equally spaced bolts 43. A packing ring 44 is interposed between the cylinder head and the gland cap. Two dowel pins 45 extend from the inner side of the gland cap 40 and into the socket 37 and are received in holes in the head 46 of an adjusting rod 47 which head is rotatably received in the socket 37.

The rod 47 projects through the hole 38 in the end of the socket and extends along the longitudinal axis of the cylinder C to a point just short of the open end of the cylinder. The end of the bolt is threaded and on the thread a travelling adjusting nut 48 is received.

The upper end or open end of the piston P is received in the lower end or open end of the cylinder C and is slidably engaged by the circular bushing 49 which is inserted in an enlarged portion of the lower end of the cylinder and extends for a considerable distance along the cylinder. The interior diameter of the bushing is less than the internal diameter of the cylinder and the same diameter as the outer diameter of the piston. The long bushing stabilizes the jack against buckling. Between the outer end of the bushing 49 which terminates short of the open end of the cylinder C and the gland cap 50, suitable packing such as "chevron" packing rings is interposed. By means of suitable bolts 52 passing through the gland cap 50 and engaging a flange 53 secured to the outside of the lower end of the cylinder C the packing is forced into sealing engagement with the cylinder C, the bushing 49 and the piston P.

A short distance from the open or upper end of the piston P a piston head 54 is secured to the inner side of the piston, as by welding. The piston head is located in such a position as to just clear the depressed portion of cylinder head 35 when the open end of the piston is in contact with the inner face of the flat portion 36. The piston head 54 is circular in outline, closely fits inside the piston, has a central opening 55 therethrough of larger diameter than the adjusting rod 47, and has two diametrically opposed circumferential slots or oil passages 56 arranged as shown in Fig. 8.

Extending from a position near the lower side of the piston head 54 to a position near the closed end of the piston P, are two diametrically opposed parallel guide strips or splines 57 secured to the inner wall of the piston. The keys or splines 57 are rectangular in shape and serve to prevent rotation of the adjusting nut 48 relative to the piston P. The nut has two circumferential grooves or slots 58 extending parallel to the bore into which the splines loosely fit so

as to leave passages for fluid to pass freely between the piston and cylinder. The sides of the nut are also cut away as shown in figure 9 so as to allow free passage of fluid between the piston and cylinder. It will be observed that the grooves or slots 56 in the piston head 54 are substantially at right angles to the grooves 58 in the nut.

The length of the adjusting rod 47 is such that it extends to a point just short of the piston-receiving or lower end of the cylinder, and the piston and cylinder are of such lengths as to allow a generous overlap say about twenty inches in a twelve foot cylinder, and with a piston of approximately the same length as the cylinder. When the piston is fully inserted in the cylinder the end of the adjusting rod 47 terminates an appreciable distance from the closed end of the piston P.

The amount of extension of the piston relative to the cylinder is limited by the adjusting nut 48 coming in contact with the piston head 54, and is controlled by varying the position of the adjusting nut 48 on the adjusting rod 47. This may readily be done even while the apparatus is attached to the furnace by withdrawing the bolts which hold the gland cap 40 in position and rotating the cap and thus the adjusting rod 47 by means of the dowel pins 45. The adjusting nut is retained against rotation by the splines 57 and moved along the threaded end of rod 47 to the desired position by appropriate rotation of the adjusting rod. It is also evident that the position of the adjusting nut 48 can be regulated by turning the piston relative to the cylinder, but this method in general could not be so convenient when the apparatus is operatively connected to a furnace.

To tilt the furnace to the pouring position indicated by broken lines 59 in Figure 1, oil under suitable pressure is admitted to both jacks through the passages 29 by manipulation of valve 30. It is advisable to ensure that there is no air in the jack and this can be done by allowing any air that may be present to escape through the bleed hole 39 and vent 41. To permit the furnace to return to level position, the oil is allowed to flow out of the jack through valve 30, propelled by the weight of the furnace. The furnace is supported in level position on legs 60 which are secured to the bottom of the furnace shell on the side of the furnace opposite the tilting pivots or pins 14, and rest on the foundation 16. In the level position there is no strain on the jacks.

I have provided a structure which is readily adjustable when assembled, the adjusting means being enclosed and protected. The operation of the structure is not effected by warping which is incident to the operation of a furnace and the structure is one in which dirt does not readily accumulate on exposed working surfaces and when it does accumulate it tends to be removed by any leakage of the actuating fluid. The device is very compact, simple to operate, rigid, and maximum travel is obtained for a given length of jack.

It is realized that the present invention may be embodied in constructions other than those specifically disclosed herein and therefore the disclosure is to be considered as illustrative and it is understood that various changes may be made without departing from the invention and within the scope of the claims.

I claim as my invention:

1. For use with a tilting furnace having a pivotal support about which the furnace may be tilted and a foundation, the invention which comprises means interposed between the furnace and the foundation for tilting the furnace about the pivotal support, said means including a cylinder and co-operating piston interposed between the furnace and the foundation, and means enclosed within the cylinder for regulating the length of travel of the piston relative to the cylinder, said means including an adjusting rod rotatably received in the cylinder and extending along the longitudinal axis of the cylinder, the rod having a threaded portion, a nut engaged by the threaded portion, means in the piston for restraining the rotation of the nut, the piston having a piston head through which the adjusting rod passes.

2. For use with a tilting furnace having a pivotal support about which the furnace may be tilted and a foundation, the invention which comprises means interposed between the furnace and the foundation for tilting the furnace about the pivotal support, said means including a cylinder and co-operating piston interposed between the furnace and the foundation, said cylinder having a cylinder head sealing one end thereof, the other end being open, the cylinder head having an inwardly directed depressed portion, a hole in the center of the depressed portion, a headed rod passing through said hole and extending along the longitudinal axis of the cylinder, the head of the rod being received in the depressed portion, the end of the rod being threaded, a nut engaged by the threaded portion, said piston having a closed end and an open end, the open end being slidably received in the cylinder, a piston head fixed in the piston adjacent the open end thereof, a hole in the piston head through which the rod passes, the head being located between the adjusting nut and the cylinder head when the piston is in operating position in the cylinder.

3. For use with a tilting furnace having a pivotal support about which the furnace may be tilted and a foundation, the invention which comprises means interposed between the furnace and the foundation for tilting the furnace about the pivotal support, said means including a cylinder and co-operating piston interposed between the furnace and the foundation, said cylinder having a cylinder head sealing one end thereof, the other end being open, the cylinder head having an inwardly directed depressed portion, a hole in the center of the depressed portion, a headed rod passing through said hole and extending along the longitudinal axis of the cylinder, the head of the rod being received in the depressed portion, the end of the rod being threaded, a nut engaged by the threaded portion, said piston having a closed end and an open end, the open end being slidably received in the cylinder, a piston head fixed in the piston adjacent the open end thereof, a hole in the piston head through which the rod passes, the head being located between the adjusting nut and the cylinder head when the piston is in operating position in the cylinder, and a passage for fluid arranged in the cylinder head leading into the upper end of the depressed portion.

4. For use with a tilting furnace having a pivotal support about which the furnace may be tilted and a foundation, the invention which comprises means interposed between the furnace and the foundation for tilting the furnace about

the pivotal support, said means including a cylinder and co-operating piston interposed between the furnace and the foundation, said cylinder having a cylinder head sealing one end thereof, the other end being open, the cylinder head having an inwardly directed depressed portion, a hole in the center of the depressed portion, a headed rod passing through said hole and extending along the longitudinal axis of the cylinder, the head of the rod being received in the depressed portion, the end of the rod being threaded, a nut engaged by the threaded portion, said piston having a closed end and an open end, the open end being slidably received in the cylinder, a piston head fixed in the piston adjacent the open end thereof, a hole in the piston head through which the rod passes, the head being located between the adjusting nut and the cylinder head when the piston is in operating position in the cylinder, and a passage for fluid arranged in the cylinder head leading into the upper end of the depressed portion, and a controlled fluid vent in the closed end of the cylinder.

5. For use with a tilting furnace pivotally mounted on a foundation and having a cylinder and piston unit interposed between the furnace and the foundation for tilting the furnace on its pivotal mounting; the invention herein described that comprises a universal joint positioned between the body of the cylinder and the body of the furnace for pivotally securing the cylinder to the furnace with said piston directed downward, comprising a yoke-like bracket secured to the furnace body, and means for providing a pivotal bearing between said foundation and the end of the piston.

6. For use with a tilting furnace pivotally mounted on a foundation and having a cylinder and piston unit interposed between the furnace and the foundation for tilting the furnace on its pivotal mounting; the invention herein described in a universal joint for securing the cylinder to the furnace body which comprises a trunnion collar encircling the cylinder, a yoke-like bracket on the furnace, bearing pins between the collar and bracket, and a trunnion bracket bridging the trunnion collar and connected to the cylinder and pivotally connected to the trunnion collar at right angles to the bearing pins, the yoke-like bracket being connected to the furnace at a point beyond the center line of the furnace and distant from the pivotal support.

7. For use with a tilting furnace having a pivoted support about which the furnace may be tilted and a foundation for the support, the invention which comprises fluid operated extensible means including a hollow cylinder and a co-operating hollow piston telescopically received in the cylinder, the cylinder having a closed upper end and open lower end, the piston having a closed lower end and open upper end, the open end of the piston being received in the open end of the cylinder, and means including an adjusting rod within the cylinder and the piston for adjusting the length of travel of the piston, said rod being adapted to be rotated, and a perforate piston head within the open end of said hollow piston through which said rod extends, together with a non-rotatable stop member secured in adjustable threaded engagement with said adjusting rod in said piston and cylinder assembly, whereby the rotation of said rod is effective to regulate the extent of the outward movement of said hollow piston relatively to said cylinder.
